UNITED STATES PATENT OFFICE.

SAMUEL COHEN, OF BROOKLYN, NEW YORK.

METHOD OF AND APPARATUS FOR AMPLIFICATION AT DIFFERENT FREQUENCIES.

Application filed December 19, 1922. Serial No. 607,776.

My invention relates to a method of and apparatus for amplifying fluctuating, alternating or oscillatory current, such, for example, as received in radio or high frequency 5 signaling systems for purposes of telephony, telegraphy, and signaling in general.

In accordance with my invention, the high or radio frequency current is first amplified, as by a thermionic amplifier; the amplified 10 current is then rectified by any suitable type of rectifier, as a crystal detector, thermionic rectifier, or the like, and the rectified current is then amplified at lower or audio frequency by the same device or thermionic amplifier 15 which amplifies the incoming current at radio or other high frequency.

My invention resides in the method and apparatus of the character hereinafter described and claimed.

For an understanding of my method, and for an illustration of some of the various 20 forms of apparatus embodying my invention, reference may be had to the accompanying drawing, in which:

Fig. 1 is a diagrammatic view of apparatus in accordance with my invention, involving a transformer coupling between amplifier and rectifier.

Fig. 2 is a diagrammatic view of apparatus 30 embodying my invention, in which the amplifier and rectifier are coupled by an inductance or auto-transformer.

Fig. 3 is a diagrammatic view of apparatus embodying my invention in which the amplifier and rectifier are coupled by a resistance.

Fig. 3^a is a fragmentary diagrammatic view illustrating a thermionic rectifier which may be utilized as the rectifier of any of the 40 arrangements of Figs. 1, 2 and 3.

Fig. 4 is a diagrammatic view of a modified form of my invention in which the rectifier is of the thermionic type and disposed in the same vacuum with the thermionic amplifier.

Referring to Fig. 1, A represents an antenna or other absorption structure, or a conductor upon which exist high frequency oscillations, as of radio frequency, representing 50 telephonic, telegraphic or other messages or signals. Between the antenna A and the earth or counter-capacity E is connected the primary P of an oscillation transformer and a variable condenser C for tuning the antenna path to the frequency of the received 55 energy, it being understood that condenser

C may be in parallel to the primary P for long wave reception. Across the secondary S of the oscillation transformer is connected the variable condenser C¹ for tuning the secondary circuit to the frequency of the received energy. One terminal of the secondary circuit is connected to the control electrode, or other control means, as the grid g of the vacuum tube or thermionic amplifier 60 V, having in addition to the grid the anode a and the cathode or filament f, the latter supplied by current from the battery b in quantity controllable by the variable resistance or rheostat r. The other terminal of the secondary S is connected through the condenser C² with the cathode or filament f. The vacuum tube V is of the so-called audion type, and is preferably of the type utilizing pure 65 electron discharge, as when the vacuum within the tube V is extremely high.

In the anode circuit are connected the battery or source of current B, the telephone receiver T, shunted by the condenser C³, which by-passes the high frequency current around 70 the telephone T, and the primary P¹ of a radio frequency transformer, preferably shunted by the variable condenser C⁴ for tuning the circuit to the frequency of the received energy. In inductive relation to the primary P¹ is the secondary S¹ of the radio frequency transformer, preferably shunted by the variable condenser C⁵ for tuning the circuit to the frequency of the received 75 energy. In series with the secondary S¹ is a rectifier R, of any suitable type, here indicated as a so-called crystal rectifier or detector, such as galena, silicon, etc., in contact with another conductor, or one employing copper pyrites in contact with zincite. In 80 series with the rectifier R is the primary P² of a low or audio frequency transformer 85 whose secondary S² is bridged across the aforesaid condenser C², which exhibits low reactance for by-passing the received high 90 frequency oscillations around the secondary S².

A condenser C⁶ is preferably bridged across the primary P² for by-passing the high frequency oscillations from the secondary S¹ around the primary P².

By thermionic amplifying action, well understood in the radio art, the incoming high or radio frequency current is amplified by the thermionic device V, the amplified high frequency current appearing in the anode circuit and therefore traversing the primary P¹ and condenser C³. By transformer action 100 105 110

- similar amplified high frequency currents appear in the secondary S^1 , and this amplified current of high or radio frequency is rectified by the device R, there appearing in the circuit of the primary P^2 a current of lower or audio frequency corresponding with the modulation in accordance with speech or sound waves of the received energy, or in accordance with any other modulation or interruption of the received oscillations. The audio frequency current traversing the primary P^2 is, therefore, one corresponding with the rectified radio or high frequency received oscillations, with the result that the secondary S^2 impresses upon the grid circuit of the amplifier V correspondingly high potentials at audio frequency, causing amplification at audio frequency by the same thermionic amplifier V of the audio frequency current which appears in the anode circuit of the amplifier V traversing the telephone T, and there reproducing speech or other signal as a result of double amplification, that is, amplification at both radio and audio frequencies.

In Fig. 2, the arrangement is in general similar to that of Fig. 1, except in lieu of the transformer P^1 , S^1 there is utilized the high impedance or inductance L in series in the anode circuit with the telephone T. The radio frequency inductance or impedance L couples the anode circuit to the circuit of the rectifier R. The rectifier circuit is in shunt to the impedance L and comprises the condenser C^r , the rectifier R and the primary P^2 in series with each other, the condenser C^r being of low reactance for the amplified high or radio frequency current.

The high or radio frequency current is amplified by the thermionic amplifier V, the amplified current appearing in the anode circuit and traversing the inductance L and the condenser C^s . The amplified current is transferred to the rectifying circuit, where it is rectified, and the low or audio frequency current by the transformer P^2 , S^2 again varies the potential of the grid at the low or audio frequency, with the result that the audio frequency current is amplified by the same thermionic detector V.

In Fig. 3 the arrangement is in general similar to that of Fig. 2, except that in lieu of inductance L is employed a high non-inductive or other suitable resistance Z for effecting a resistance coupling between the anode circuit of the amplifier V and the rectifier circuit, transferring to the latter the amplified high or radio frequency current. In this case again, amplification is double in the sense that there is an amplification first at high or radio frequency and then at lower or audio frequency.

Any suitable type of rectifier may be utilized at R in the arrangement of Figs. 1, 2 and 3. A thermionic rectifier may be em-

ployed, such, for example, as indicated at Fig. 3^a, the same comprising an evacuated bulb D having the incandescent cathode or filament f¹ and the plate or anode a¹, the filament being supplied with current from a battery b¹ controlled by a rheostat r¹. The anode a¹ and cathode f¹ are connected in series in the rectifier circuit in place of the rectifiers R of Figs. 1, 2 and 3.

In the arrangement of Fig. 4, the amplified high or radio frequency current in the circuit of the anode a traverses the primary P^1 of the radio frequency transformer, preferably shunted by the tuning condenser C^4 , and the condenser C^3 by passing the telephone receiver T.

In this instance the thermionic amplifier is provided with a second anode a², connected through the secondary S^1 of the oscillation transformer and the primary P^2 , and a suitable portion of the battery B with the cathode f. The secondary S^1 is preferably shunted by the condenser C^5 for tuning to the high or radio frequency.

The amplified high or radio frequency current appearing in the secondary S^1 is rectified by the thermionic action between the cathode f and the anode a², the path between these electrodes being asymmetrically conducting. There accordingly flows through the primary P^2 a rectified current, and the low or audio frequency component impresses a low or audio frequency potential upon the grid g, with the result that there appears in the circuit of the anode a and telephone T an amplified low or audio frequency current which is translated into a message or signal by the telephone T.

As to Figs. 1, 2, 3 and 4, it will be understood that the telephone T may be replaced by a primary winding of an audio frequency transformer of one or any suitable number of further stages of amplification.

It will be understood as to condensers C^4 in Figs. 1, 2 and 4 and the condenser C^5 in Figs. 1 and 4, that they are preferably used for tuning purposes, but that they may be dispensed with, particularly if the transformer windings P^1 , S^1 of Figs. 1 and 4, or the inductance L of Fig. 2, are suitably proportioned or designed, especially when the frequency of the received energy lies within a relatively narrow range of frequencies. For reception of so-called "short" waves, these condensers may be omitted, particularly when the windings P^1 , S^1 of Figs. 1 and 4 and the inductance L of Fig. 2 are so constructed or wound as to have a minimum of distributed capacity.

It is further desirable, as regards the windings P^2 , S^2 of the audio frequency transformers of Figs. 1 to 4 inclusive, that they should have high inductance values and small or negligible distributed capacity, to enhance transformation between P^2 and S^2 at audio frequencies only.

In Fig. 2 the circuit L , C^4 is an anti-resonant circuit exhibiting very high or almost infinite impedance. The condenser C^4 shunting the inductance L may in some instances be omitted, particularly in case the inductance L^3 exhibits high inductance and has low or negligible distributed capacity.

The degree of vacuum within the amplifier tube V is of importance in that when the tube is "soft", that is, when the tube contains rarified gaseous medium, the double amplification of the character described is not nearly so effective, if at all effective, as in the case when the tube is "hard", that is, when the tube contains practically no gas and the discharge is a pure or substantially pure electron discharge.

What I claim is:

1. The combination of an electron tube system having a cathode, an anode and a control electrode arranged in the order named, an auxiliary anode mounted adjacent said cathode opposite said first mentioned anode and control electrode, an input circuit including said cathode and said control electrode, an output circuit including said first mentioned anode and said cathode and a separate circuit inductively coupled to each of said circuits and connected with said auxiliary anode, a responsive device connected in said output circuit, said first mentioned anode, control electrode and cathode cooperating for the amplification of incoming signaling energy at different frequencies and said auxiliary anode and cathode cooperating to rectify the incoming signaling energy.

2. The combination of an electron tube system comprising an evacuated vessel, a pair of anodes, a cathode and a control electrode, an input circuit interconnecting said cathode and control electrode, an output circuit including one of said anodes and said cathode in series with a loop resonant circuit and a responsive device connected therein, a series circuit connected between a point of high potential in said output circuit and said other anode, said series circuit including a loop resonant circuit electromagnetically coupled with said first mentioned loop resonant circuit, said first mentioned anode, cathode and control electrode cooperating

for the amplification of incoming signaling energy at different frequencies and said second mentioned anode and cathode cooperating to rectify the incoming signaling energy for actuating said responsive device.

3. The combination of an electron tube system comprising an evacuated vessel, a pair of anodes, a cathode and a control electrode, an input circuit interconnecting said cathode and said control electrode, an output circuit interconnecting said cathode and said other anode, said output circuit including a tuned circuit, a responsive device and a source of potential, an auxiliary circuit including a tuned circuit coupled with said first mentioned tuned circuit and connected at one end with said other anode and at the other end with an intermediate point along 70 said source of potential in said output circuit, said auxiliary circuit being inductively coupled with said input circuit whereby radio frequency signaling energy impressed upon said input circuit is amplified by the 75 cooperative action of said first mentioned anode, cathode and control electrode and delivered to said auxiliary circuit for reduction in the frequency thereof and the signaling energy at reduced frequency is impressed 80 upon said input circuit for actuating said responsive device.

4. A signal receiving circuit comprising in combination an electron tube having an evacuated vessel, a pair of anodes, a cathode, 85 and a control electrode, an input circuit interconnecting said control electrode and said cathode, an output circuit interconnecting one of said anodes and said cathode, said output circuit including a responsive device 90 and an auxiliary circuit connected between said other anode and a point of high potential in said output circuit and having high frequency and low frequency windings connected therein and inductively coupled with 95 said output and input circuits, respectively, for effecting amplification of incoming signaling energy at different frequencies and the rectification of the signaling energy for operation of said responsive device. 100

In testimony whereof I have hereunto affixed my signature this 15th day of December, 1922.

SAMUEL COHEN.
